[57] CLAIM

The ornamental design for a liquid therapy pad, as shown and described.

DESCRIPTION

FIG. 1 is a top perspective view of a liquid therapy pad illustrating our new design;

FIG. 2 is a bottom perspective view thereof;

FIG. 3 is a top elevational view thereof;

FIG. 4 is a bottom elevational view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken line showing in FIGS. 1-6 is for illustrative purposes only and forms no part of the claimed design.
